UNITED STATES PATENT OFFICE.

RAYMOND C. MITCHELL, OF SPRINGFIELD, OHIO, ASSIGNOR, BY MESNE ASSIGNMENTS,
TO BARBER-COLMAN COMPANY, A CORPORATION OF ILLINOIS.

GRINDING MACHINE.

Application filed August 16, 1920. Serial No. 403,999.

To all whom it may concern:

Be it known that I, RAYMOND C. MITCHELL, a citizen of the United States, residing at Springfield, in the county of Clark and 5 State of Ohio, have invented certain new and useful Improvements in Grinding Machines, of which the following is a specification.

My invention relates to work driving 10 means for grinding machines and the like, wherein the work is rotated as it is fed past a working tool. In grinding machines for plain cylindrical or tapered work, such as the machine herein shown for illustration 15 of my invention, it is usual to mount the grinding wheel at a relatively fixed station and to reciprocate in front of the grinding wheel station a table carrying the head-stock and tail-stock, between which the 20 rotatable work is mounted. Customarily, in such constructions, the rotary element of the head-stock, for driving the work, is driven by a belt or other frictional driving 25 arrangement that is exterior to the frame of the machine.

An object of my invention is to provide a novel positive driving mechanism in connection with a head stock, reciprocable with the work carrying table, doing away with belting, and building the mechanism into the machine with minimum exposure of running parts. One construction embodying my invention is shown in the accompanying drawings, wherein Fig. 1 is a front 30 elevation of a grinding machine; Fig. 2 is a plan view of the head-stock end thereof; Fig. 3 is a fragmentary vertical sectional elevation of parts shown at the left in Fig. 2; Fig. 4 is a fragmentary vertical section 35 of portions of the machine in substantial continuation to the right of the construction shown in Fig. 3; Fig. 5 is a vertical cross-section on line 5—5 of Fig. 3; Fig. 6 is a vertical section on line 6—6 of Fig. 4.

In known fashion, the machine base 10 carries the slide-table 11 to be automatically reciprocated in front of a grinding wheel at station 12. The grinding wheel, of course, is preferably mounted for the usual 40 adjustments, and equipped for hand and automatic micrometer-feed transversely to the path of travel of the work and for other manual and automatic functioning appro-

priate to this type of mechanism; but these details are not shown herein as my present 55 invention has no concern with them and in these regards constructions that are old and well-known in the art may be used. Also it will be understood that the work-table, equipped on its under side with a rack 13, 60 may be hand-moved or automatically reciprocated through variable range of stroke by gearing 14, which may receive power in any suitable fashion, as from exterior multi-step pulley 15, the power train including 65 usual manually-controlled speed-changing gearing; the table-travel being governed by automatic reversing mechanism, controlled to vary its throw, by the usual trip-dogs 16. All of these various devices also may 70 be of known construction which it is unnecessary here to illustrate or describe in full, as they are well understood in the art.

The tail-stock-unit 17 and the head-stock 75 unit 18, carried by the reciprocating table 11 are mounted thereon for longitudinal adjustment to accommodate work of different lengths between their center-points and for lateral adjustment to vary the angle of presentation of the work with respect to the 80 grinding wheel, and these capabilities may be afforded by structures of a character well known in the art. The details of such adjustable mounting may vary, but the construction illustrated provides, on the slide table, a plate 19 pivoted centrally as at 20 for angular adjustment of the work relative to the longitudinal line of travel of the table, its arcuate ends 21 being adapted to be clamped in adjusted positions, or different angular settings, in the clamp-guides 85 22. The head-stock and tail-stock are longitudinally slidable on such plate 19 in usual fashion, and may be clamped in longitudinal 90 adjusted position thereon as by means of clamping bolts 23; all typical of known constructions.

It will be understood, also, that shop-machinery other than grinders may present work-handling mechanism of kindred sort to that described and that my invention is not restricted specifically to the mechanism illustrated in the matters thus described.

Novelly, I provide in conjunction with a 105 suitable work-handling mechanism involv-

ing a reciprocable work table and a longitudinally and laterally adjustable head-stock, as above generalized, positive built-in gearing for driving the head stock at different selective speeds, arranging the driving means to accommodate the various adjustments of the head stock and also the bodily reciprocation of the head stock with the slide-table as above described. Specifically, 25 represents the rotatable work-driving element of the head stock assembly, preferably housed as at 26 and carrying a gear 27. With such gear there meshes the driving pinion 28 fast on a flexible shaft 29 that is journaled in bearings carried by the body casting 30 of the head stock. As the forward end of shaft 29 will be thrown to different transverse and angular positions owing to the adjusting movement of the head stock, it is made with two sections 29^a and 29^b flexibly connected by a suitable universal joint 31 the shaft-section 29^b being mounted to slide through but rotate with a beveled gear 33 to which power is communicated from bevel gear 34 fast on the vertical shaft 35 which constitutes a positively-positioned part on the table for actuating the movably-positioned parts. This shaft 35 extends down below the level of slide table 11 and its lower end is connected by beveled gears 36, 37 with a longitudinal table-carried, main shaft 38 to which power is applied by base-carried gearing, in the manner hereinafter described.

35 An advantageous construction for the mounting of these table-carried gearing and shaft parts is illustrated in Fig. 3. Block 40 secured to the slide table has sleeve 41 to afford adequate bearing for the long hub 37' of gear 37 which is contained in the grease-chamber 42 of the block, to which chamber access may be had through the end cap 43; and on the block 40 is mounted a vertical standard or hollow post 44 affording at its lower and upper ends bushed bearings for the shaft 35. The top of standard 44 has a reduced portion or pivot-end 44' on which may turn the collar 45 of a horizontally-disposed elongated housing 46 that is long enough to accommodate the section 32 of flexible shaft 32-29 and to give such shaft ample range of axial movement. A cap 47, closing the front opening of the housing 46 affords adequate bearing for the elongated hub 33' of the gear 33. It will be understood, of course, that as the head-stock is adjusted transversely the housing 46 turns pivotally and gear 33 may planet slightly around the gear 34; the shaft-section 29^b sliding through the gear 33 to accommodate this slight change of relative position (or sliding more to accommodate any longitudinal adjustment of the head stock on the swing plate 19) so that the positive drive connections from the positively positioned

gear 34, including flexible shaft 29 and its sliding connection with gear 33, permit of all requisite movements of the head-stock without loss of connection.

The table-carried main shaft, 38, is gear-driven from a power shaft on the base 10, preferably through speed-changing gearing. The shaft 38, where it extends beyond the block 40, is made of square or other non-circular section (Fig. 5) and within the base 10 of the machine it engages the squared aperture of a gear 50, the long hub of which is adequately journaled in a bracket 51 that extends transversely across the base near the center thereof. This shaft may also extend through and bear in the end wall 52 of the base 10. Power is applied to the gear 50 through base-carried driving connections as follows: A multi-speed pulley 53 mounted on a power-shaft 54 (Figs. 4 and 6) communicates power through pinion 55 to a gear 56 that is mounted on a shaft 57, journaled in the brackets 51 and 58 of the base. Between this shaft 57 and gear 50 on the sliding shaft 38 a change speed gearing is arranged, illustrated as a two speed construction, although (if direct motor drive for the power shaft be employed in lieu of the multi-speed pulley 53) the number of speed changes may be suitably increased. As shown, a sliding clutch element 60 on the shaft 57, rotatable with said shaft and controlled by a shipper-lever 61, may engage the clutch-hubs of either the small gear 62 or the large gear 63 loose on shaft 57 and respectively meshing with large gear 64 and small pinion 65, these being fast on an intermediate shaft or jack-shaft 66 that is journaled in the brackets 51 and 58, the gear 64 meshing with that gear, 50, through which the shaft 38 slides. Of course the shipper lever 61 is controlled from the exterior of the machine, as by suitable link connections 67 to handle 68, so that the driving pulley 53 may be connected through either the lower-speed train 62, 64 or the higher-speed train 63, 65, 64 with the driving gear 50 for the shaft 38 that in turn drives the working element of the head stock.

It will be apparent that by the construction described I provide a simple, rugged and efficacious gear drive for the head stock that is as durable and free from liability to slippage or other disorders as is possible, and that in so doing I clear the head stock end of the machine of objectionable belting connections and other impedimenta that have generally been employed in connection with the driving of the head stock.

While I have herein described in some detail a particular construction which I have found to be advantageous and desirable, it will be understood by those skilled in the art that many changes in details of construc-

tion may be made without departure from the spirit of my invention within the scope of the appended claim.

I claim:

- 5 A grinding machine having, in combination, with a base and a table reciprocable on the base, a shaft mounted to turn on a vertical axis at one end of the table, a plate pivoted on the table and having a head stock
10 at the end adjacent said shaft and swingable transversely with the plate relative to the vertical shaft on the table, said head stock being mounted for longitudinal adjustment on the plate and having a horizontally disposed work driving element, said vertical shaft having its lower end passing through the table and terminating a substantial distance above the table, a horizontal longitudinally extending shaft having a gearing
15 connection with the upper end of said vertical shaft, said gearing connection permitting the horizontal shaft to swing in a horizontal plane on the axis of said vertical shaft and also permitting the longitudinal movement of the horizontal shaft in a direction perpendicular to the axis of the vertical shaft, a flexible coupling between said horizontal shaft and the driving element of the head stock, said coupling being adapted to permit the head stock to be swung bodily relative to the vertical shaft transversely of said table on the pivotal center of said plate, and means operatively connected with the lower end of said vertical shaft for positively driving the same, and maintaining driving engagement therewith during the travel of the vertical shaft with the table.

RAYMOND C. MITCHELL.
